UNITED STATES PATENT OFFICE.

JESSE D. LYON, OF CINCINNATI, OHIO, ASSIGNOR TO THE A. S. BOYLE COMPANY, OF CINCINNATI, OHIO, A CORPORATION OF OHIO.

FLOOR WAXER AND POLISHER.

Application filed February 28, 1924. Serial No. 695,858.

To all whom it may concern:

Be it known that I, JESSE D. LYON, a citizen of the United States of America, and a resident of Cincinnati, in the county of Hamilton and State of Ohio, have invented a new and useful Improvement in a Floor Waxer and Polisher, of which the following is a specification.

An object of my invention is to provide a floor waxing and polishing device that will require a minimum of effort in adjusting the device for use.

Another object is to provide a device of this character in which the polishing and waxing cloths are automatically clamped upon the bottom plate when the handle is in such position as it would assume in use and in which said cloths are loosely retained in position subject to ready removal when the handle is in a vertical position.

These and other objects are attained by means described herein and disclosed in the accompanying drawings in which:

Fig. 1 is a longitudinal cross sectional view of a device embodying my invention.

Fig. 2 is a fragmental perspective view of a bottom plate forming a detail of my invention.

Fig. 3 is a perspective view of a top plate forming a detail of my invention.

Fig. 4 is a perspective view of a cloth retaining clamp forming a detail of my invention.

Fig. 5 is a perspective view of a clamp lock and handle rod, etc.

The device comprises a base consisting of a top and a bottom plate. The bottom plate 6 has a depression 7 in its upper face, the depression 7 being bounded by an upwardly extending flange 8. A felt pad 9 covers the bottom of the plate 6 and extends around the top and sides of the flange 8 and for a short distance over the surface of depression 7. The pad 9 is detachably secured in position by means of a top plate 10 which fits into the depression 7 in the bottom plate 6. The plate 10 has depending projections 11 at its ends and sides for engaging the edges of the pad 9 which rest in the depression 7 of the bottom plate. Threaded studs 12 extend upwardly from the depression 7 in the plate 6. The stud may be provided by using screws countersunk in the bottom of plate 6 or in any desired manner. The top plate 10 has a central depression 13 in which are

located spaced perforations 14 registering with the studs 12 and through which the studs extend into the depression 13. Nuts 15 are mounted upon the ends of studs 12. The structure just described provides a positive securing means for holding the felt pad 9 in position, all edges of the pad being clamped between the plates.

The top plate has a pair of upwardly extending lugs 16 located one on either longitudinal side of the depression 13. Aligned perforations 17 extend horizontally through the lugs 16 and a suitable bolt 18 extends through perforations 17 in the lugs and through bore 19 in handle socket 20 whereby a pivotal handle mounting is provided. The handle socket has the usual longitudinal bore 21 extending partially through its length and suitable perforations 22 communicating therewith through which rivets or screws may pass and engage a handle (not shown) within the bore 21.

With this floor waxer and polisher there is employed a soft cloth or fabric which engages the surface to be polished. Usually several layers of such cloth are employed and when waxing a floor a small quantity of wax is placed between several thicknesses of cloth which is then placed upon the bottom of the polisher and the ends of the cloth secured upon the top of the polisher.

The cloth securing means of my invention is as follows:

The top plate 10 has parallel slots extending across opposite ends thereof and several layers of polishing cloth 24 are passed about the bottom and ends of the plate 6 and extend over the top across the slots 23 in the top plate. The clamping member indicated generally as 25 comprises a pair of metal plates 26 each having a downwardly turned flange 27 adapted to seat in slots or grooves 23. The plates 26 are secured one at each end of a spring steel strip 28 which lies between the lugs 16 on the plate 10, the flanges 27 engaging the cloth 24 in the slots 23. The clamping member 25 may be of one piece but for economy of manufacture the strip 28 is made of spring steel while the plates 26 having depending flanges 27 are made of ordinary sheet steel. The plates are secured to the end of the springs in any suitable manner such as striking lugs through the plates into perforations in the end of the spring or by

spot-welding, riveting or any of the other well known means for securing metals one upon the other.

The handle socket 20 has parallel faces 31 surrounding the ends of the bore 19 and extending transversely to the axis of said bore. The end of the handle socket may be likened to a cylinder attached longitudinally along one of its curved sides to the handle member and having the side opposite such place of joinder cut away to leave a flat face 29. The distance from the center of bore 19 to the edge of the face 29 is materially less than the distance to the edge of the curved surfaces 30. Therefore when the socket member 20 is assembled in the polisher it may be turned about the pivotal mounting on the bolt 18 to assume a vertical position at which time the face 29 is clear of the spring steel strip 28 so that the clamping member 25 rests lightly in position. When the socket member 20 is turned out of a vertical position such as any angle less than 90 degrees to the horizontal the curved face 30 will act as a cam on the strip 28 which will cause the flanges 27 to be pressed downwardly and outwardly in the groove 23 in the top plate.

A polishing cloth inserted between the flange 27 and groove 23 will thus be tightly clamped in place whenever the handle socket is in a position other than perpendicular to the top plate. When the polisher is in use the handle will always necessarily be either parallel with the plates as in polishing the floor under a piece of furniture or at an angle of about 30 to 45 degrees to said plates.

When it is desired to insert or remove a cloth it is necessary only to place the handle socket in a vertical position at which time clamping member 25 will be free to move, make the desired insertion or removal of the cloth. The weight of the clamping member will retain the cloth in position and prevent accidental separation. As soon as the handle is moved from a vertical position the clamping member automatically binds the polishing cloth as described above.

What I claim is:

1. In a floor waxer and polisher, the combination of a base comprising top and bottom plates, the top plate being adapted to be mounted on the bottom plate, a felt pad mounted on the bottom plate and having its edges secured between the plates, means to secure the plates one upon another for clamping the edges of the felt pad between said plates, upwardly extending lugs on the top plate, said top plate having spaced lateral slots across its upper face, a strip of fabric extending from one of the slots over the lower face of the felt pad and terminating at the other slot, a spring member having depending flanges for seating in the slots in the top plate and engaging the strip

of fabric, a handle socket member pivotally mounted adjacent its one end between the lugs on the top plate above the spring member, a pair of cam faces on the end of the handle socket adjacent the pivotal mounting, a flat face on the said end of the handle socket intermediate the cam faces, the socket member being adapted in its vertical position to have its flat face parallel to and spaced from the spring member and in a position other than vertical to have one of its cam faces in engagement with the spring member for clamping the cloth between the flanges and the walls of the slots in the top plate.

2. In a floor polisher and waxer the combination with a base having a pair of parallel grooves in its upper face adjacent opposite ends thereof, a strip of cloth having its one end inserted in one of said grooves and passing around the lower face of the base and terminating in the other groove, a clamping member comprising an integral spring and flanged plates, the flanges on the plates seating in the grooves and engaging the cloth therein, a handle socket member pivotally mounted intermediate the ends of the clamping member, a flat face on the end of the handle socket member extending transversely to the longitudinal axis thereof and arcuate cam faces on the socket member on opposite sides of the flat face, the socket member being adapted in a vertical position to have its flat face parallel to and spaced from the clamping member and in a nonvertical position to have one of its cam faces in engagement with the clamping member for securing the cloth in the grooves in the base.

3. In a cloth clamping mechanism for a floor polisher and waxer having a grooved base, the combination with a handle socket member pivotally mounted upon the base, a flat face on one end of the socket member, arcuate cam faces on opposite sides of said member adjacent the flat face, a clamping member comprising an integral flat spring strip and flanged plates mounted at the ends thereof, the flat face of the socket member being parallel to and spaced from the spring strip when said socket member is positioned perpendicular to the base, and one of the cam faces engaging the spring strip and moving the flanged plates into clamping engagement with the walls of the grooves in the base against the yielding resistance of the spring strip whereby the ends of a cloth inserted between the flanges and the grooves may be secured when the socket member is nonperpendicular to the base.

4. In a floor waxer and polisher, the combination of a base having spaced grooves in its top face, an integral spring clamping member, depending flanges on the clamping member for seating in the grooves and

a handle socket member pivotally mounted above and intermediate the ends of the clamping member, the end of the handle socket member being spaced from the clamping member when said handle member is perpendicular to the base and when in a nonperpendicular position to engage the clamping member for moving the flanges into binding engagement with the walls of the grooves.

5. In a floor waxer and polisher the combination with a base having a pair of grooves in its upper face, of a clamping member comprising a flat spring strip and integral depending flanges extending from the ends thereof and a handle socket member having cam faces about its one end pivotally mounted on the base above the clamping member for assuming an inoperative position with the cam faces spaced from the

clamping member and an operative position with a cam face engaging the clamping member against the yielding resistance of the spring strip whereby the flanges are moved into binding engagement with the walls of the grooves in the base.

6. In a floor polisher the combination with a base member having grooves in its upper face, a cloth clamping member comprising an integral flat spring having depending flanges for engagement in the grooves in the base, and a handle socket member pivotally mounted upon the base and engaging the spring for clamping the flanges in the grooves in the base.

In testimony whereof, I have hereunto subscribed my name this 19th day of February, 1924.

JESSE D. LYON.
